TO ROBERT LEE GRAY, OF WASHINGTON, DISTRICT OF COLUMBIA

VARIABLE-COMPRESSION INTERNAL-COMBUSTION ENGINE

Application filed April 23, 1928. Serial No. 272,288.

This invention has been devised in order to provide improvements in the construction of internal combustion engines, by the adoption of which, provision is made for the degree of compression of the explosive charges being automatically maintained at a constant, no matter what the volume of the charges drawn into the engine may be.

With these engines as at present constructed, the cubical area of the compression chamber in each cylinder remains the same throughout, so that when the throttle is fully open and full charges are being drawn into such chamber, and the engine is running at full speed, the degree of compression of each charge reaches its maximum, while when the throttle is partially closed and the charges drawn in are correspondingly reduced, the degree of compression also is reduced. Thus the resultant power obtained by the expansion of the gases on each explosion is not as great as it should be, when running at slow speed, proportionately to the power obtained when running at high speeds, simply because the lessened degree of compression provides less expansive force on explosion.

The present invention has been devised with the object of overcoming this drawback and to provide that equal compression may be obtained automatically upon all variations of the charges, that is, a small charge will receive compression to the same degree as a large charge, and thus better power results are obtained.

The invention provides for this degree of compression being fixed to accord with the nature of the oil fuel employed, as it is well known that the different grades of fuel give best results when their resultant gases are compressed to certain degrees of compression. Thus for benzine, one degree of compression may be fixed as the "constant," for alcohol, another, and so on.

The invention may be carried out by providing each engine cylinder with a movable head or floating piston arranged to move vertically within the cylinder, with relation to the travel of the piston, so as to vary the area of the space between the piston and such head, and the head is moved mechanically re-

sponsive to the pressure of the fuel as it is compressed to automatically maintain the fixed "constant."

It is a further object of the invention to provide a mechanical lock for the floating piston to securely lock the piston in its upper position or during the firing stroke of the engine. A still further object resides in the provision of an auxiliary piston and spring or fluid pressure equal to the "constant" pressure and which actuates the floating piston under the action of the pressure in the cylinder. A further object resides in the provision of the gear ring mounted on the floating piston which is provided with teeth and grooves meshing with corresponding teeth and grooves on the floating piston and the worm gear on the piston forms a mechanical lock against movement except when rotated by the auxiliary operating piston by means of a worm gear meshing with the worm gear on the floating piston. Further objects reside in the fluid pressure control and the cam construction for the intake and exhaust valves as well as the construction of the ports in the floating piston themselves.

Still further objects will be apparent from the following description taken in connection with the accompanying drawings in which like reference characters indicate corresponding parts throughout and in which:

Fig. 10 is a side view of the floating piston of the cylinder of Fig. 8.

Fig. 11 is a top view of the cylinder of Fig. 8, and

Fig. 12 is a section through the cylinder of a modified motor construction.

The engine according to Figs. 1 to 7 comprises four cylinders 1, 2, 3 and 4, each having a piston 5 therein and surrounded by a 10 casing 10 comprising a water jacket 50. In the upper part 6 of each cylinder, which is preferably of a greater diameter than the lower part, a floating piston or head 11 is provided which is grooved to provide teeth 12 15 on the upper part and grooves 13 on the lower part to receive the usual sealing rings 47. Over the teeth 12, a worm gear ring 15 fits which is provided with corresponding inner teeth 14 which mesh in the grooves formed 20 by the teeth 12 in the piston. The outside of the ring 15 is provided with a worm gear 65 cut in its periphery and this ring is adapted to rotate in the upper part 90 of the cylinder which is above and is of a greater diameter 25 than portion 6. The ring 15 is rotatably retained in the portion 90 by means of a retaining plate 33 which is bolted down on the cylinder by bolts 34. The floating piston slides vertically in the portion 6 of the cylinder, when the ring 15 is rotated, and it is prevented from rotating by a key and slot arrangement, the key 96 being secured in the cylinder and the slot 66 in the piston. The piston therefore slides on the key by means 35 of its slot.

Each floating piston 11 has a pair of openings 91 therein preferably on opposite sides and the interior of the piston is divided into two parts by means of partition 92 so that 40 each part has one opening 91 therein. Also each part of the piston has a valve therein of which 19 is the exhaust valve and 23 the intake valve for the fuel. These valves seat in openings 97 in the bottom of the floating 45 piston. For the purpose of conveying the fuel and exhaust gases, an exhaust manifold 35 and an intake manifold 43 is provided in the part 6 of the casing 10 and these manifolds cooperate with the respective openings 91 in the piston.

The valves 19 and 23 are spring pressed to urge them on their seats at all times and such springs 46 are preferably mounted in a recess 24 on the top of the floating pistons 55 and bear thereagainst. These valves are operated by cams 28 mounted on a common cam shaft 27 constructed in sections and connected together in spaced relation by flexible couplings 30. This cam shaft is mounted in ball 60 bearings 29 mounted in extensions 31 on and preferably integral with the floating pistons. As the floating pistons move vertically approximately upwardly and downwardly together, the entire shaft 27, cams 28 and bearings 29 move likewise and the couplings 30

allow for any slight movement of a single floating piston irrespective of the others. At one end of the shaft, a bevel gear 38 is secured which meshes with a bevel gear 39 mounted on connecting shaft 40. This shaft 40 is slidably mounted in supports 42 and has a square cross-section at the lower end 32 which slidably fits into a corresponding section 41 of a drive shaft 98. The bevel gears 38 and 39 are maintained in mesh by 70 the retaining member 36 which has thrust bearings 44 therein. The shaft 40 therefore rises and falls with the cam shaft but motion is always imparted to the cam shaft due to the coupling 32 and 41, that is, the square end 32 sliding in the corresponding member 41.

Each cylinder 1 to 4 is provided with a spark plug 9 preferably provided in portion 6 of the cylinder wall. Also each cylinder 85 may comprise an actuator or regulator for the floating piston or a single actuator can be used for all of the floating pistons which includes a double piston rod 53 having a piston 56 and 57 at each end and sliding in a cylinder 25. At the lower end of this cylinder a valve mechanism 61 rotates in a casing 26 and the valve and casing are preferably circular but other types of valves can be used. The casing 26 communicates with the interior of the cylinder 4 to which it is secured by means of pipe 60 and opens into the cylinder 25 by means of an opening 72 in the casing 26. The valve is operated by a lever 62 having a slot 87 in the outer end thereof in which a rod 63 is adjustably secured and this rod 63 is suitably operated by the engine by an eccentric mechanism 101. The slot 87 permits for the regulation of the operation of the valve and this is preferably carried out automatically by a speed responsive device 83 mounted on a shaft 86 and operated by the engine by means of pulley 85. The rod 63 slides in an abutment 82 of the speed responsive device and by shifting this abutment on the shaft 86 the rod 63 will also be shifted. The casing 26 has a further opening 73 which by means of a suitable pipe communicates with the intake manifold of the carburetor, not shown, which is for the purpose of returning the gases used 100 to actuate the piston rod 53 for re-use.

The piston rod 53 is provided with a plurality of teeth 64 which are adapted to mesh with the gear 52 which in turn operates the shaft 45, worm gear 51, worm gear ring 15 and finally the respective floating piston or pistons 11. The piston rod 53 may be actuated by fluid pressure entering through pipe 59 and acting on piston 56 or a spring 55 or both can be used, the latter also acting on the piston 56. The spring 55 may be adjusted by means of an adjusting plate 98 having a screwthreaded spindle 99 and a nut head 100 for effecting adjustment.

Fig. 8 shows a sleeve-valve motor which 130

comprises the usual sleeves 76 and 77, one within the other and both reciprocating in a cylinder which is surrounded by a water jacket 50. The sleeves are actuated in the usual manner and the upper part of the cylinder comprises a block 67 between which and the cylinder wall the upper parts of the sleeves project. This block has internal grooves and teeth 71 which are adapted to mesh with corresponding grooves and teeth 93 of the floating piston 11. The lower end of the floating piston has a piston or sealing ring 47 in a suitable groove and in the center a spark plug 9 is inserted. The block 67 also has a ring 81 therein to form a tight seal between it and the sleeve 77. At the top of the floating piston and on the block 67, the gear ring 15 is provided which imparts rotation to the floating piston by the pin 68 mounted therein and projecting into the groove 94 in the piston 11. The gear ring 15 is operated by the same means as in the construction of Figs. 1 and 2 and is held in place by a plate 33 and bolts 34 which also extend through the holes 95 in the block 67 and into the engine casing, to thereby secure the plate 33 and the block 67 on the cylinder. In this sleeve valve motor the floating piston rotates as it is adjusted vertically. The control for the piston is the same as in the construction of Figs. 1 and 2 and the passage 60 leading to the control device projects through the block 67 and the sleeves.

The modification according to Fig. 12 shows a side valve engine having the spark plug 9 and the valve 70 at the side of the cylinder. The floating piston 11 is actuated by the usual gear ring and grooves and teeth as shown and operating in a manner similar to the construction of Figs. 8 to 11.

The most important features of applicant's invention may be outlined as follows: Constant compression is obtained under all conditions irrespective of the speed of the engine. Increased compression takes place on top center before explosion. The adjustable heads or floating pistons follow the power piston during a part of the explosion stroke but are securely locked against upward movement during explosion stroke.

Regarding the increased compression taking place on top center before explosion, it is explained that, if desired, the valve 61 can be operated to close the pipe 60 and open the pipe 73 before extreme top dead center is reached. This will result in the pressure on the piston 56 forcing the rod 53 downwardly to also force the floating piston downwardly thereby adding to the pressure of the compressed fuel to increase the efficiency.

The operation of the engine is as follows:

When the piston 5 of cylinder 4 is coming up on compression stroke the valve 61 has opened the connection between pipe 60 and opening 72 to allow the pressure in the cylinder 4 to be communicated into the space 54 of the cylinder 25. On the top of the piston 56 is a pressure of, for instance, 100 lbs. which is supplied either by means of a spring or compressed air or both. Assuming the floating piston 11 and the pistons 56 and 57 to be in their lowest position, these members will not be moved or adjusted so long as the pressure of the fuel being compressed remains under 100 lbs. As soon as a pressure slightly greater than 100 lbs. of the fuel is reached the pistons 56 and 57 together with rod 53 will move upwards, thereby actuating the gear 52, shaft 45, worm gear 51, and worm gear ring 15. Rotation of the latter causes the floating piston to rise, due to the teeth and grooves 12 and 14, until the piston 5 has reached top center, whereupon the valve 61 will close the pipe 60 to prevent any further upward movement of the floating piston. The valve 61, however, immediately opens opening 72 to the pipe 73 which is connected to the intake manifold, thereby releasing the pressure in the lower part of the cylinder 25 to allow the spring or pressure on piston 56 to actuate the floating piston downwardly when the pressure in the power cylinder falls during and after the firing stroke. The floating piston will be moved to its lowest position, and is in that position prepared for another compression stroke.

Any degree of compression can be used and one can be altered to another by simply altering the pressure on the piston 56 or by altering the tension of spring 55, or both, mainly depending upon the specific fuel used.

The floating piston can only move vertically and cannot rotate when used on an overhead valve system but rotates when used in a side valve engine or in a sleeve valve engine.

A centrifugal governor as shown in Fig. 2 is preferably used to bring about a change in compression for high motor speeds, as it is a well known fact that a motor operating at high speed requires a higher compression to obtain the best results. As the engine speed increases the governor will cause the valve 61 to close at a period just before top center of piston 5 to thereby render a higher compression ratio than the fixed ratio. As the engine speed decreases the governor will cause the valve to close as the piston 5 reaches top center and thereby reduce the compression to the set amount. By the use of the double compression principle, the compression can be maintained until the crank has passed over the top center, so that the full force of the explosion will be delivered to the crank shaft when it is in the most efficient position, which is just past top dead center.

In a multi-cylinder engine, one cylinder 25 can control all of the floating pistons. In this case the valve 61 will only be open on the compression stroke of the cylinder on which it is secured and thereby adjust all of the floating pistons in the engine. In such a con-

struction, the floating pistons will remain practically stationary one they have been adjusted and will only slightly move vertically in response to change of speed when possibly more or less fuel is drawn into the cylinder and therefore an adjustment of the compression is necessary. Such an arrangement excludes the connection 62 since the pressure of the fuel in the cylinder 25 is not relieved at any time but remains practically at the "constant" set for the specific fuel used. The valve 61 is, of course, closed during firing, exhaust and intake stroke and is open only during a part of the compression stroke, that is, during only the latter part of the compression stroke.

A manual control can be provided for the shaft 45 so that in case of uniform load and speed of the engine, one setting would be sufficient. In that case, the valve 61 should be disconnected in closed position. Also in case the valve or control mechanism should become inoperative for any reason, such as a breakdown, the manual control will provide for the setting of the engine so that its proper operation may be continued.

In the engine of Figs. 1 and 2, the spark plug may be inserted in the floating piston instead of in the cylinder wall.

30 I claim as my invention:

1. A variable compression internal combustion engine comprising a cylinder; a power piston in said cylinder; a floating piston slidably mounted in the upper part of the cylinder and having teeth and grooves therein; means provided around said floating piston having teeth and grooves meshing with the teeth and grooves of the floating piston; and means for automatically actuating said first-40 named means to provide an approximate constant pressure for the compressed fuel charge.

2. A variable compression internal combustion engine comprising a cylinder; a power piston in said cylinder; a floating piston slidably mounted in the upper part of the cylinder and having teeth and grooves therein; a worm gear ring provided around said floating piston and having teeth and grooves therein meshing with the teeth and grooves of the floating piston; and means for actuating said gear ring to adjust the floating piston in the cylinder to provide an approximate constant pressure for the compressed fuel charge.

3. A variable compression internal combustion engine comprising a cylinder; a power piston in said cylinder; a floating piston slidably mounted in the upper part of the cylinder and having teeth and grooves; a worm gear ring provided around said floating piston and having teeth and grooves therein meshing with the teeth and grooves of the floating piston; means for actuating said gear ring to adjust the floating piston in the cylinder to provide an approximate constant pressure for the compressed fuel charge; and

an intake valve and an exhaust valve mounted in said floating piston.

4. A variable compression internal combustion engine comprising a cylinder; a power piston in said cylinder; a floating piston slidably mounted in the upper part of the cylinder and having teeth and grooves; a worm gear ring provided around said floating piston and having teeth and grooves therein meshing with the teeth and grooves of the floating piston; means for actuating said gear ring to adjust the floating piston in the cylinder to provide an approximate constant pressure for the compressed fuel charge; an intake valve and an exhaust valve mounted in said floating piston and being spring pressed; and a cam shaft mounted in ball bearings on said floating piston and having cams thereon adapted to actuate said valves.

5. A variable compression internal combustion engine comprising a cylinder; a power piston in said cylinder; a floating piston slidably mounted in the upper part of the cylinder and having teeth and grooves; a worm gear ring provided around said floating piston and having teeth and grooves therein meshing with the teeth and grooves of the floating piston; means for actuating said gear ring to adjust the floating piston in the cylinder to provide an approximate constant pressure for the compressed fuel charge; an intake valve and an exhaust valve mounted in said floating piston and being spring pressed; a cam shaft mounted in ball bearings on said floating piston and having cams thereon adapted to actuate said valves; and means for rotating said cam shaft.

6. A variable compression internal combustion engine comprising a cylinder; a power piston in said cylinder; a floating piston slidably mounted in the upper part of said cylinder and having teeth and grooves therein; a gear ring provided around said floating piston having two sets of teeth and grooves therein, one set being on the inside of the ring which mesh with the teeth and grooves of the floating piston; and means cooperating with the other set of teeth and grooves in the gear ring for automatically actuating said ring to adjust the floating piston in the cylinder to provide an approximate constant pressure of the compressed fuel charge.

7. A variable compression internal combustion engine comprising a cylinder; a power piston in said cylinder; a floating piston slidably mounted in the upper part of said cylinder and having teeth and grooves therein; a gear ring provided around said floating piston having two sets of teeth and grooves therein, one set being on the inside of the ring which mesh with the teeth and grooves of the floating piston; a shaft having a worm gear thereon meshing with the other set of teeth and grooves of the ring; a second gear mounted on said shaft; and means cooperating with

said second gear for automatically actuating said ring to adjust the floating piston in the cylinder to provide an approximate constant pressure of the compressed fuel charge.

8. A variable compression internal combustion engine comprising a cylinder; a power piston in said cylinder; a floating piston slidably mounted in the upper part of said cylinder and having teeth and grooves therein; a gear ring provided around said floating piston having two sets of teeth and grooves therein, one set being on the inside of the ring which mesh with the teeth and grooves of the floating piston; a shaft having a worm gear thereon meshing with the other set of teeth and grooves of the ring; a second gear mounted on said shaft; a piston and rod mounted in an auxiliary cylinder, said rod having teeth thereon meshing with the gear; and a valve communicating with the interior of the cylinders adapted to automatically control the piston and rod to adjust the floating piston in the cylinder to provide an approximate constant pressure of the compressed fuel charge.

9. A variable compression internal combustion engine comprising a cylinder; a power piston in said cylinder; a floating piston slidably mounted in the upper part of said cylinder and having teeth and grooves therein; a gear ring provided around said floating piston having two sets of teeth and grooves therein, one set being on the inside of the ring which mesh with the teeth and grooves of the floating piston; a shaft having a worm gear thereon meshing with the other set of teeth and grooves of the ring; a second gear mounted on said shaft; a piston and rod mounted in an auxiliary cylinder, said rod having teeth thereon meshing with the gear; a valve communicating with the interior of the cylinders adapted to automatically control the piston and rod to adjust the floating piston in the cylinder to provide an approximate constant pressure of the compressed fuel charges; and means for operating said valve including a speed responsive device for adjusting the constant degree of compression at different speeds of the engine.

10. A variable compression internal combustion engine comprising a cylinder; a power piston in said cylinder; a floating piston mounted in the upper part of the cylinder; a ring mounted around and adapted to actuate said floating piston; and means for automatically actuating said ring to provide an approximate constant pressure for the compressed fuel charge.

11. A variable compression internal combustion engine comprising a cylinder; a power piston in said cylinder; a floating piston mounted in the upper part of the cylinder; a ring mounted around and adapted to actuate said floating piston; means for automatically actuating said ring to provide an

approximate constant pressure for the compressed fuel charge; and means for retaining said ring in place.

12. A variable compression internal combustion engine comprising a cylinder; a power piston in said cylinder; a floating piston mounted in the upper part of the cylinder and having two openings in the bottom thereof, two openings in the side thereof and a partition therein; an intake valve mounted in the floating piston on one side of the partition and seating in one of the bottom openings and cooperating with one of the side openings; an exhaust valve mounted in the floating piston on the other side of the partition and seating in the other of said bottom openings and cooperating with the other of said side openings; a gear ring mounted around said floating piston; and means for automatically actuating said ring to adjust the floating piston in the cylinder thereby providing an approximate constant pressure for the compressed fuel charge.

13. A variable compression internal combustion engine comprising a cylinder; a power piston in said cylinder; a floating piston mounted in the upper part of the cylinder and having two openings in the bottom thereof, two openings in the side thereof and a partition therein; an intake valve mounted in the floating piston on one side of the partition and seating in one of the bottom openings and cooperating with one of the side openings; an exhaust valve mounted in the floating piston on the other side of the partition and seating in the other of said bottom openings and cooperating with the other of said side openings; a gear ring mounted around said floating piston; means for automatically actuating said ring to adjust the floating piston in the cylinder thereby providing an approximate constant pressure for the compressed fuel charge; and a cam shaft for actuating said valves.

14. A controlling device for a variable compression internal combustion engine comprising an auxiliary cylinder secured to the engine; a piston and rod in said cylinder and having teeth in the rod thereof; means for applying a constant pressure on the piston depending upon the specific fuel used in the engine; a valve for communicating the pressure of compression of the fuel in the engine to the piston; and means associated with the teeth of the piston rod for conveying the movement of the piston and rod to the engine for specific adjustment to maintain an approximate constant pressure for the compressed fuel charge.

15. A controlling device for a variable compression internal combustion engine comprising an auxiliary cylinder associated with the engine; a piston and rod in said cylinder; means for applying a constant pressure on the

- piston depending upon the specific fuel used in the engine; a valve for periodically communicating the pressure of compression of the fuel in the engine to the piston and rod; and means associated with the piston rod for conveying the movement of the piston rod to the engine for specific adjustment to maintain an approximate constant pressure for the compressed fuel charge. 5
16. A variable compression internal combustion engine comprising a cylinder; a power piston in said cylinder; a floating piston slidably mounted in the upper part of said cylinder and having teeth and grooves in the side thereof; a gear ring provided around said floating piston and having inner and outer sets of teeth and grooves therein, the inner set meshing with the teeth and grooves of the floating piston; means for retaining said gear ring on the floating piston; and means associated with said outer set of teeth of the ring for automatically actuating said gear ring to adjust the floating piston in the cylinder to provide an approximate constant pressure for the compressed fuel charge. 10 75
17. A variable compression internal combustion engine comprising a cylinder; a pair of sleeve valves adapted to reciprocate in said cylinder; a block mounted on the top of said cylinder and projecting into the cylinder between which and the cylinder the upper part of the sleeves reciprocate and having teeth and grooves on the inner side; a floating piston mounted to move vertically in said block and having teeth and grooves meshing with the teeth and grooves of the block; a ring mounted around and adapted to rotate said floating piston; and means for actuating said ring to adjust the floating piston in the cylinder to provide an approximate constant pressure for the compressed fuel charge. 15 80 85
18. A variable compression internal combustion engine comprising a cylinder; a pair of sleeve valves adapted to reciprocate in said cylinder; a block mounted on the top of said cylinder and projecting into the cylinder between which and the cylinder the upper part of the sleeves reciprocate and having teeth and grooves on the inner side; a floating piston mounted to move vertically in said block and having teeth and grooves meshing with the teeth and grooves of the block; a ring mounted around and adapted to rotate said floating piston; means for actuating said ring to adjust the floating piston in the cylinder to provide an approximate constant pressure for the compressed fuel charge; and means for retaining said ring on said block. 20 90 95 100 105 110 115 120 125
19. A variable compression internal combustion engine comprising a cylinder having teeth and grooves in the upper part; a valve provided at the side of the cylinder; a power piston in said cylinder; a floating piston mounted to rotate and move vertically in said cylinder and having teeth and grooves therein adapted to mesh with the teeth and grooves of the cylinder; a ring mounted on the top of said cylinder and around said floating piston, said ring and floating piston being adapted to rotate together and the floating piston being slidably mounted in the ring; means for retaining said ring on the piston; and means for actuating said ring to adjust the floating piston in the cylinder to provide an approximate constant pressure for the compressed fuel charge. 25 70 75 80 85 90 95 100 105 110 115 120 125 130

In testimony whereof I affix my signature.
